UNITED STATES PATENT OFFICE.

MAURICE ROSENFIELD, OF NEW YORK, N. Y.

PRINTING-MACHINE.

1,098,056.

Specification of Letters Patent. Patented May 26, 1914.

Application filed October 11, 1911. Serial No. 654,021.

To all whom it may concern:

Be it known that I, MAURICE ROSENFIELD, a citizen of the United States, and a resident of New York city, borough of the Bronx, and State of New York, have invented certain new and useful Improvements in Printing-Machines, of which the following is a specification.

My invention relates to printing machines utilizing a D-roller with an engraved plate, and printing upon a continuous ribbon or tape.

The objects I have in view are to equally space the impressions upon the ribbon or tape by means operating independently of the bed or platen of the press; to make such mechanism simple and easily accessible, and to make the feed entirely automatic.

A further object is to provide means for keeping the reels of printed ribbon distinct from one another.

These and further objects will more fully appear from the following specification and accompanying drawings, considered together or separately.

In the drawings, Figure 1 is a plan view of an apparatus embodying my invention. Fig. 2 is a longitudinal sectional view of the same taken upon the line 2—2 of Fig. 1. Fig. 3 is a front elevation of the same, but with the D-roller in the position shown by dotted lines in Fig. 2. Fig. 4 is a partial sectional view, taken on the line 4—4 of Fig. 5. Fig. 5 is an end view of the same. Fig. 6 is a sectional view of the bearings for the gripper shaft. Fig. 7 is a diagrammatical view of the operating parts at rest in the position they assume before printing. Fig. 8 is a similar view, showing the parts at the beginning of movement to the printing position and while the ribbon is being fed across the D-roller. Fig. 9 is a similar view, showing the parts in position while drawing the ribbon from the reel and winding it upon the spool. Fig. 10 is a detailed longitudinal section of the take-up shaft; and Fig. 11 is a cross-section of the same.

In all of the views like parts are designated by the same characters of references.

The press comprises the usual platen or bed carrying the printing surface and the usual D-roller, the ribbon passing around the latter and between it and the bed. The D-roller is given a partial revolution, engaging the ribbon with the printing surface, and then a partial revolution in the opposite

direction, thus making a double impression and a clear printing. While the flat portion of the D-roller is opposite the bed and there is a space between the two, the ribbon is fed forward for another impression. The invention relates to the feeding mechanism. 60

The frame 1 of the press is of the usual type, having standards 2 which carry bearings 3 for the D-roller 4. Below the D-roller is the usual platen or bed 5 sliding on the frame and supported upon rollers 6. The platen is moved in one direction by means of a cam 7 on the D-roller which engages with a cam 8 on the platen or bed, and is moved in the opposite direction by means of a strap 9 connected to a weight (not shown). A printing surface 10 is carried on the bed and may be of the character usually employed for this purpose. The ribbon is supported so that it travels over the bed or platen, and between the latter and the D-roller. The printed ribbon is either wound upon a reel above and to the back of the D-roller, or passes to a basket or other receptacle. The embodiment chosen for illustration has six separate ribbons which are simultaneously printed; the number may be diminished or increased without changing the principle of the invention. 75 80 85

11 is a reel of unprinted ribbon or tape 12. In some situations this reel may not be employed; the supply of ribbon or tape being taken from a basket or other receptacle. The ribbon passes over the platen, as shown, 90 and leads through a staple 13. This staple is secured to a bar 14 attached to the back or flat side of the D-roller. The staple is of such a size that it makes a tight fit with the ribbon sufficiently to move the ribbon 95 and rotate the reel 11 when the latter is used, or when not employed, to lift the ribbon out of its receptacle. It is, of course, understood that where a plurality of ribbons is used, as shown, that there is a staple for each ribbon. The ribbon passes over the cam face of the D-roller and extends through a guiding staple 15, which makes a loose fit with the ribbon. This staple is supported upon a bar 16 attached to the 105 curved surface of the D-roller. Any means of attachment may be employed for the bar, and it is desirable that the bar shall be adjustable in position along the surface of the D-roller to accommodate different feeds. 110 The ribbon next passes from the D-roller around a roller 17. This roller is for the

purpose of moving and winding the ribbon and is preferably rubber covered. The ribbon is next wound upon a spool 18 supported upon a shaft 19. When certain kinds of ink 5 are used which do not dry rapidly, the ribbon cannot be immediately wound. In this situation the spool is dispensed with and the shaft 19 directly engages with the surface of the roller 17, the ribbon being 10 pinched between the two and drops down where it can be caught in a basket or other receptacle. The roller 17 is mounted in bearings 20, which in turn are supported on arms 21. These arms are carried upon a 15 shaft 22 mounted on brackets 23 carried by the standard 2.

The device for feeding and determining the amount of ribbon which is necessary for each impression, consists of a positive gripping mechanism adapted to be engaged at the proper time with the ribbon. This gripping mechanism is supported in bearings 24, the mechanism being supported on the gripping shaft 25. This gripping shaft 25 carries a gripping plate 26, having teeth 27. On one end of the shaft 25 is a wiper 28, shown in the embodiment chosen for illustration as in the form of a roller. The bearings 24 are mounted on housings 29, one of 30 these housings being solid and the other hollow to permit the shaft 25 to extend through it. The shaft 25 is mounted in such relation to the roller 17 that upon the shaft being partly rotated the teeth of the gripping plate may be caused to engage with the surface of the roller. This partial rotation of the shaft is made by the engagement of the wiper 28 and a cam 30. This cam 30 is carried by the D-roller. It is 40 adapted to be engaged with the wiper by the rotation of the D-roller, causing the cam to come in contact with the wiper, rotating the latter and carrying the gripper into contact with the ribbon, pressing the same 45 against the roller 17 and preventing retrograde movement. The further movement of the cam 30 in relation to the wiper 28 is a sliding movement, the wiper not responding in a rotary direction more than enough 50 to engage the gripper with the roller 17 with sufficient pressure to prevent retrograde movement of the ribbon.

For the purpose of guiding the ribbon to the roller 17, it passes through a staple 31, 55 which is carried by a frame 32, which in turn is carried by arms 21. For the purpose of disengaging the gripper from the ribbon, a spring 33 is provided, engaging with the gripper plate at one end and with 60 the frame 32 at the other. This spring is of the compressing type, *i. e.*, it is expanded by the action of the cam and wiper, and its elasticity causes it to assume its normal contracted form. For the purpose of limiting 65 the movement of the gripper, an adjustable

screw 34 is provided, one end engaging the gripper plate, when at its extreme retracted position.

For the purpose of permitting the feeding mechanism to be elevated for examination 70 and repair, the parts described are mounted upon a swinging support. This support comprises a pair of arms 35 mounted on the shaft 22, which in turn carries arms 36. These arms 36 support the shaft 19. The 75 connection between the arms 35 and 36 is by means of a shaft 37. The arms 35 and 36 are separated by means of a spring 38.

For the purpose of separating the spools of wound and printed ribbon and to cause 80 them to wind easily upon their spools, division plates 39 are provided, said plates being pivoted to the shaft 37. These plates have notches which engage the shaft 19, as shown, and are held in place by gravity. 85 An arm 40 on one end of the shaft 22 is provided for holding the roller 17, shaft 19 and wiper in place and for imparting the necessary pressure of the wiper upon the cam 30. A spring 41 holds this arm downward. For limiting the movement of the shaft 22, caused by the tension of the spring 41, an arm 42 is mounted on the end opposite from the arm 40, and this arm 42 carries an adjusting screw 43, which engages 95 with a lug 44 on the standard 2. These parts are normally in the position shown in full lines in Fig. 2, but by twisting the shaft 22 (spring 41 having been disconnected) the parts may be raised to the dotted 100 line position shown in Fig. 2, rendering the rollers and gripping mechanism readily accessible.

The means for imparting tension to the roller 17 are as follows:—This roller is 105 mounted upon bearings 45 (see Fig. 4) on a stub-shaft 49. A drum 46 is carried on the same stub-shaft, by bearings 48, adjacent to one end of the said roller. In this drum is a spiral spring 47. The bearings 110 illustrated are ball-bearings, which I prefer, as they may be adjusted with a minimum of lost motion, and require little lubrication, so that the ribbon will not become soiled, as is the case where plain bearings 115 are used. The stub-shaft is carried on one of the arms 21. A band, string or wire 50 is secured to the D-roller and also to the drum 46 and is wound one or more times around the latter. One end of the roller 120 17 is provided with ratchet teeth 51 and a pawl 52 on the drum 46 engages with these teeth. I prefer to make the drum 46 slightly smaller than the roller 17 for a purpose to be described. The shaft 19 is so mounted 125 on the arms 36 as to be readily removable therefrom, the details being shown on Figs. 10 and 11. The bearing boxes are provided with notches as shown, and blocks 53 engage in these notches and hold the 130

ends of the shaft in position. Spring clips 54 secured to the blocks frictionally engage with the bearing boxes and hold the blocks in position.

5 The D-roller is operated by the usual handles 55, secured to the shaft 56. The D-roller has the usual pad 57. The cam 30 is secured to the D-roller so as to move in time therewith by means of a dove-tailed 10 block shown on Fig. 3. By means of this block the cam may be removed and a different one, with a face of more or less extent, substituted.

15 The operation of the entire apparatus is as follows: A supply of ribbon is mounted upon the reel 11 and led through the staple 13 around the face of the D-roller, through the guide staples 15 and 31, and over the feed roller 17. The ribbon may then be 20 wound upon the spool 18, or if desired, may be simply pinched between the roller 17 and shaft 19. This operation is repeated with the additional ribbons, so that there 25 will be six ribbons side by side in the apparatus. In printing, the printing surface is inked in the usual manner and the D-roller makes a partial revolution and returns. This gives the usual double impression upon the ribbon.

30 The operation is best shown in Figs. 7, 8 and 9. The beginning of the operation is shown in Fig. 7, the printing surface having been inked and a surplus of ribbon wound upon the spool 18 and stretched 35 smoothly over the D-roller. The D-roller is turned first in the counterclockwise direction, as in Fig. 8. The roller 17 is prevented from rotating and the ribbon in contact with the surface of this roller is 40 held against further retrograde movement by means of the gripper, which is caused to engage with the ribbon by means of the cam 30, engaging with the wiper 28, thus twisting the shaft 25. The ribbon being 45 anchored in contact with the roller 17 and the D-roller continuing to move the ribbon will slide through the staple 13. The cam 30 slides along the face of the wiper 28, preventing backward rotation of the latter 50 and holding the gripper in contact with the ribbon and the roller 17. The gripper remains in this position until the cam passes its total working length in contact with the wiper 28. As soon as it disengages, the 55 spring 33 will disengage the gripper from the ribbon and hold it in contact with the stop 34. The roller 17 will be now free to rotate, and with it the ribbon will be moved. The ribbon will then receive its 60 first printing between the face of the D-roller and the printing surface 10. The ribbon or tape between the D-roller and the reel 11 will now be slack and rest on the platen. While the D-roller is rotating, the 65 wire 50 will rotate the drum 46 against the

tension of the coiled spring 47, the pawl 57 at the same time will pass idly over the ratchet teeth. During that portion of the movement of the D-roller after the cam 30 has cleared the wiper 28, the movement of 70 the drum 46 will be slightly faster than the movement of the roller 17, owing to the fact that in the embodiment chosen for illustration, the wire and ribbon both being moved by contact with the curved surface of the D-roller will move at the same rate of speed, and the roller 17 being moved by engagement of the ribbon and being larger than the drum will be moved slower. As a result of this, the spring will be wound 75 up slightly in excess of the amount of ribbon moved over the roller 17. The object of this is to accommodate lost motion between the ratchet wheel 51 and pawl 52.

80 On the return movement of the D-roller, as shown in Fig. 9, the pawl 52 will engage with one of the ratchet teeth 51 and the spring 47 uncoiling will tend to rotate the roller 17 in the reverse direction. This will wind up the ribbon on the spool 18 85 as fast as it is moved to it by the D-roller. When the cam 30 comes in contact with the wiper 28, it will have no other effect than to slide upon the periphery of the latter, tending to rotate it in the counterclockwise direction, and will merely tend to move the gripper plate in the same direction as it is moved by the spring 33 which has been holding the gripper in contact 90 with the stop 34. The printed ribbon will 100 continue to be wound up on the spool 18, so long as the D-roller continues to move in the clockwise direction. On again moving the D-roller in the counterclockwise direction, the ribbon will be fed as before.

95 It is apparent from the foregoing description that the ribbon is automatically fed on the D-roller toward the roller 17 by means of the D-roller, the staple 13 thereon and the roller 17 and the gripper 27.

110 As described, a certain length of ribbon is advanced over the bed by the clockwise movement of the D-roller, the ribbon being fed by the frictional contact of the staple 13 with the ribbon, and the supply thus fed being taken up by the roller 17 actuated by the spring 47. This length of ribbon thus advanced is greatly in excess of that subsequently to be fed, *i. e.*, it is greater than the distance which is to separate the several impressions. On the reverse movement of the D-roller, a portion of the ribbon that has been fed to the roller 17 is drawn back; the gripper acting for a determined period of time during the movement of the D-roller prevents all of this ribbon previously fed by the clockwise movement of the D-roller from being fed backward. This amount, which may be measured by the angular length of the effective surface of the cam 30, 120 125 130

when reduced to the radius of the D-roller, constitutes the feed. It is apparent that by removing the cam 30 and substituting one of different angular distance, the feed of the ribbon may be increased or decreased.

It is understood that the wiper 28 is shown complete merely for the purpose of illustration, and is not necessarily an entire circle.

10 The wiper 28 is elastically engaged with the cam 30 by means of the spring 41, so that the wear of the two surfaces is properly compensated for.

In accordance with the provisions of the 15 patent statutes, I have described the principle of my invention, together with the apparatus which I now consider to represent the best embodiment thereof; but I desire to have it understood that the apparatus shown 20 is merely illustrative and that the invention can be carried out in other ways.

Having now described my invention, what I claim as new and desire to secure by Letters Patent, is:—

25 1. A D-roller printing press having, in combination with the D-roller, a feeding roller, means for engaging a ribbon with the D-roller and also with the feeding roller, and means controlled by the movement of 30 the D-roller for arresting retrograde movement of the ribbon, said means engaging the ribbon with the feeding roller.

2. A D-roller printing press having, in combination with the D-roller, a feeding 35 roller adapted to be turned in one direction by a ribbon actuated by the movement of the D-roller, a spring for turning the feeding roller in the other direction, a gripper adapted to grip the ribbon against the feeding 40 roller, and connections between the gripper and the D-roller for actuating the gripper.

3. A D-roller printing press having, in combination with the D-roller, a feeding roller, a drum, a pawl and ratchet connection 45 between the feeding roller and the drum to permit the roller to turn freely in one direction, a spring for rotating the drum in the opposite direction, a connection between the D-roller and the drum, and a 50 gripper to grip the ribbon against the feeding roller, said gripper being actuated by the D-roller.

4. A D-roller printing press having, in combination with the D-roller, a feeding roller, a gripper adapted to grip the ribbon 55 against the feeding roller, a wiper for engaging the gripper and a cam on the D-roller for actuating the wiper.

5. A D-roller printing press having, in combination with the D-roller, a feeding 60 roller, a gripper engaging therewith, said gripper being mounted upon an arm, a spring for holding the arm in position, a wiper turning with the gripper and a cam on the D-roller engaging with the wiper, the 65 spring yieldingly engaging the wiper with the cam.

6. A D-roller printing press having, in combination with the D-roller, a feeding roller, a gripper engaging with the said 70 feeding roller, a wind-up roller engaging with the feeding roller, the said feeding roller and gripper being carried upon a pivoted frame, a wiper turning with the gripper, and a cam on the D-roller and a 75 spring engaging with the frame for yieldingly engaging the wiper with the cam, the said frame also being capable of turning on its pivot for being elevated for inspection of the feeding roller.

80 7. A D-roller printing press having, in combination with the D-roller, a pivoted frame having two sets of arms, a feeding roller and a gripper mounted on one set of arms, and a set of arms mounted on the second set of arms and carrying a wind-up roller, a spring for engaging the wind-up roller with the feeding roller, a wiper on the gripper, a cam on the D-roller, and a spring on the frame for yieldingly engaging 90 the wiper with the cam.

85 8. A D-roller printing press having, in combination with the D-roller, a feeding roller, a gripper engaging with the feeding roller, a staple on the D-roller for frictionally engaging with the ribbon, and means actuated by the D-roller for engaging the gripper.

95 This specification signed and witnessed this 28th day of September, 1911.
